PIVOTALLY MOUNTED HANDBAG

Frances Victoria Lewis, New York, N. Y., assignor
of one-half to Theodore J. Ritter, New York,
N. Y.

Application January 6, 1949, Serial No. 69,450

12 Claims. (Cl. 150—34)

1 This invention relates to new and useful improvements in handbags, and, more particularly, the aim of the invention is to provide a novel and valuable handbag especially adapted for ladies' use but, of course, otherwise utilizable.

A feature of the invention is a bag body adapted normally to hang in substantially a vertical plane by virtue of its suspension from a suitable carrying handle. Along a line across the bag body and intermediate its two directions of extension at top and bottom and hence generally along a horizontal line, means are provided for pivotally mounting said bag body relative to the dependent end portions of said handle, which latter, in one now acceptable form of the invention, may be an over-the-shoulder strap.

By means of such mounting of the handbag relative to its handle, the bag body may be readily rotated around the first-named line through 180°, thereby to transpose the then bottom extension of the said body to the then location of the top extension thereof and vice versa simultaneously, so that, in accordance with further means provided, such extension of said body, when uppermost, may act as the mouth of said body to obtain access to its contents. These two mouths are openable and closable, as by use of slide fasteners; and hence whichever mouth is uppermost, that mouth may be widely opened, but meanwhile with the feeling of security that the other and now lowermost mouth is fully closed.

In a new preferred embodiment of the invention, there are a plurality of compartments in each portion of the bag body located along opposite sides of said first-named line, with the bottoms of all these compartments at or near said line. Some, several or all of these compartments may have special pockets therein, some or all of which at their mouths may be provided with slide fastener type closures, when such pockets are intended, for instance, for the storage therein of relatively small and readily spillable articles, as coins, small cosmetic articles, keys, postage stamps, and the like; while other of said pockets may have continuously open mouths, when these pockets are intended, for instance, for the storage therein of such articles as cards, memoranda carrying units, plate-like mirrors, and the like.

A large number of pockets may be provided, without unattractively adding to the bulk of the bag in terms of its thickness; and as the invention is now preferably further carried out, the same includes in effect, three main walls, two

outer ones, these to provide the two opposite side walls of the bag body as a whole, and an intermediate wall, of the same expanse substantially as said two outer walls; in which event each top (and/or bottom) of the bag and each bottom (and/or top) thereof may be provided with two slide fasteners or the like, one between one of said outer walls and the intermediate wall and one between the other of said outer walls and said intermediate wall.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view showing a now favored embodiment of the invention, closed at top and bottom and hanging from the lower end of the aforesaid handle, the latter only fragmentarily shown and so shown at its end portions.

Fig. 2 is an end elevation, looking toward the left in Fig. 1, that is, in the direction of the arrow 2.

Fig. 3 is a very much enlarged fragmentary vertical section taken through the bag at a point intermediate its two ends.

Fig. 4 is a perspective view, showing a modification.

Referring to the drawing more in detail, and first to Figs. 1-3, the handbag of the invention as here illustrated is constructed to provide four compartments 11, 12, 13 and 14. The bag body is further shown as having two outer walls 15 and 16, two end walls 17, 17, and an intermediate wall 18, this last being shown as of the same shape and expanse as the walls 15 and 16. While the bag body may assume any shape in side elevation, it is shown as of rectangular expanse in side elevation and horizontally rather elongate.

The compartments 11, 12, 13 and 14 are provided between the walls 15 and 16 and the intermediate wall 18, with the compartments 11 and 12 on one side of a pair of horizontal partitions 19, 19, and the compartments 13 and 14 on the opposite sides of said partitions. These partitions 19 may be boardlike members of any of the usual materials used for giving main strength or extra thickness to handbag or luggage walls, or of any material suitable for the purpose.

The end walls 15 and 16 are alike, and a description of one thereof, the wall 15, will suffice

as a description of both. As shown in Fig. 3, this wall is comprised of a central boardlike member 20. At the exterior face of said member, the same is covered by a suitable finishing off material, as an actual or imitation leather or any sheet material deemed satisfactory.

The intermediate wall 18 is shown as including two boardlike members 22, 22, made, for example, of the same material used for the member 20. These members 22 may be suitably bonded together, over rather a large area centrally located with respect to the expanse of the bag body side elevationally thereof, in any suitable way, as for instance, by a suitable adhesive.

Another piece 23 of suitable finishing material, for instance cut from the same material as is used for the cover sheet 21, is applied, as shown, as a liner for the compartment 12, this piece 21, in terms of the showing of Fig. 3, extending down along the upper half of one of the members 22, thence across the upper side of the partition 19 which marks the bottom of said compartment, and thence up along the upper half of the member 20. The last-named partition 19 is suitably secured in place, as in part by adhesive joinder to the portion of the sheet 23 crossing such partition as just explained. Further positional securing of said partition 19 may be obtained by adhesive joinder, to the side thereof which is its under side in terms of Fig. 3, of the portion of a liner piece for the compartment 14. This sheet 24 is dimensionally exactly like the piece 23, and the said portion of the sheet 24 is that intermediate portion thereof which crosses said partition 19.

Still speaking in terms of Fig. 3, the upper marginal portions of the sheets 15 and 23, arranged to project above the top of the member 20, are inturned toward each other, to provide a portion of a finishing off seam 25 to extend all around the wall 15 of the bag body. The lower marginal portions of said sheet 15 and of the sheet 24, these arranged to project below the bottom of the member 20, are similarly inturned toward each other to provide another portion of said seam 25, this last-named seam portion to be at the bottom of the wall 15 of the bag body. As shown in Figs. 1 and 2, said seam 25 is continuous all around the said wall 15; the portions thereof at the ends of the bag body being in part made up of inturned marginal portions of the sheet 21 and inturned marginal portions of the two end walls 17, which latter may be of one-ply flexible construction. This structure is not illustrated cross-sectionally, but will be readily understood from what is shown in Fig. 3. As will also be understood, a seam 26 running all around the side wall 16, and structurally like the seam 25, may be provided. This seam 26 has its portion which lies horizontally opposite the first-named portion of the seam 25 partially comprised of a top marginal extension of a cover sheet (not shown) for the wall structure 16 and also of a top marginal extension of a liner sheet 27, exactly like the liner sheet 23. Said seam 26 has its portion horizontally opposite the second-named portion of the seam 25 partially comprised of a bottom marginal extension of the last-named cover sheet and also of a bottom marginal extension of a liner sheet 28, exactly like the liner sheet 24. The seam 26, as shown in Figs. 1 and 2, is also continuous all around the bag body; the portions thereof at the ends of the bag body being made exactly as described in connection with the seam 25 and so including side marginal portions of both the end walls 17, 17.

The securing in place of the partition 19 at the left in Fig. 3 may be as described in connection with the other partition 19.

Still speaking in terms of Fig. 3, the two liner sheets 23 and 27 at the upper ends of their portions laid against the members 22 of the intermediate wall 18 have top marginal portions which are inturned toward each other and in a manner to be partially sandwiched between the upper ends of said members 22, to establish a finishing off seam 29. This seam 29 beyond its extension along the top of the intermediate wall 18 has downwardly extending terminal additions 29^a and 29^b leading to the tops of the end walls 17. The seams 25, 29 and 26, respectively are held as by the stitchings 30, 31 and a stitching corresponding to the stitching 30.

The compartment 12 is closed at its outer end by two strips 32 and 33, as of the same material as used for the finishing sheet; these strips 32 and 33 are stitched as at 34 and 35 longitudinally thereof to the liner sheet 23. Said strips carry the tapes of a slide fastener 36.

Said compartment 12 has a main deep central chamber, having at opposite sides two pockets, 37 and 38.

One side wall of the pocket 37 is provided by the adjacent portion of the liner sheet 23, and the opposite wall of said pocket is provided by a minor wall structure 39, comprised of a boardlike member 40 enclosed in a finishing off sheet 41 folded down over the top of said member 40 and cut so that its two lower margins may be arranged as shown to provide an upturned seam 42 whereat said minor wall structure is stitched as at 43 to the liner sheet 23. A top line of stitching 44 is applied to tack down the folded part of the sheet 41 to the upper marginal portion of the said member 40. At its opposite ends the minor wall structure 39 is suitably attached along said ends, as by stitching not shown, to the ends of the compartment 12.

One wall of the pocket 37 is provided by the adjacent portion of the said liner sheet 23, and the opposite wall of said pocket is provided by a minor wall structure 45, comprised of a boardlike member 46 faced at opposite sides by finishing off sheets 47 and 48 which along their tops are inturned toward each other to establish a seam 49 above the top of the member 46 and which along their bottoms are arranged as shown to establish a seam 50 below the bottom of the member 46. The seam 49 is held by a line of stitching 52, and the seam 50 is held, and coupled to the liner sheet 23, by a line of stitching 51. The opposite ends of the wall structure 45 are attached to the ends of the compartment 12 as explained in connection with the wall structure 39. Strips 53 and 54 similar to the strips 32 and 33 are extended across the mouth of the pocket 37; said strips 53 and 54 carrying the tapes of a slide fastener 55, and the strip 53 being held by the stitching 52, with the strip 54 attached to the liner sheet 23 by a line of stitching 56.

The compartment 14, it will be noted, is constructed interiorly, and to provide the pockets 51 and 58 corresponding in nature, respectively, to the pockets 37 and 38, exactly as is the compartment 12 in this respect, that is, the pocket 51 has its mouth openable and closable by a slide fastener 59 corresponding to the slide fastener 55 for particularly serving the pocket 37; while said compartment 14 is provided with strips 60 and 61 corresponding to the strips 32 and 33 for closure of the compartment 12 itself, these strips

60 and 61 carrying a slide fastener 62 corresponding to the slide fastener 36.

As partially shown in Fig. 3 in the case of the compartment 11, this compartment, and also the compartment 13, may be arranged interiorly thereof exactly as described in connection with the compartments 12 and 14, that is, so that each of these compartments will have a pair of pockets, one of which having an open mouth and the other having a mouth closable by a slide fastener.

Also, as partially indicated in Fig. 3, and as shown in Figs. 1 and 2, the mouth of the compartment 11 is illustrated as openable and closable by a slide fastener 63, arranged like the fastener 36, and the mouth of the compartment 13 is illustrated as openable and closable by a slide fastener 64, arranged like the fastener 62.

The partitions 19, 19 may or may not be placed along the longitudinal center-line of the bag body; but as here shown, they are placed along such line, thereby making the compartments 11 and 12 of the same depth as the compartments 13 and 14. At any rate, aligned with each other preferably along said line are two suitable fittings 65, 65 each secured to one of the end walls 17. The opposite end portions of the over-the-shoulder strap, or other desired handle, 66, are apertured or slotted, for dependable securement to said fittings.

The slider-actuators of the various slide fasteners for the closable-mouth pockets in the bag body may be made large enough to constitute readily legible indicia-bearing tags, or tag equivalents may be carried by the last-named pockets, or indeed by all the pockets.

It is to be understood that the straps of this handbag may be removed and then the handbag may be carried under the arm.

Referring to the modification shown in Fig. 4, the bag body here illustrated as shaped like the bag body of Fig. 1 is designated 67. This is shown as, for example, of the same external appearance as the bag body of Fig. 1, and it may be assumed to be compartmented as already described; in which connection it will be observed that the slide fasteners 68, 69, 70 and 71 may be taken to correspond, respectively, to the main slide fasteners 63, 36, 64 and 62. With the partitions 19 present as already described, or with some other suitable interior construction provided whereby the bottoms of the compartments corresponding to the compartments 11 and 12 are separated from the bottoms of the compartments corresponding to the compartments 13 and 14, the means permitting the bag body to be rotated through 180° relative to the lower ends of the handle is here shown as comprising a rod 72 extending centrally through the bag body substantially midway between its top and bottom, cylindrical enlargements 73 at opposite ends of said rod and beyond the ends of the bag body, and a ring 74 rockably carried by each of said enlargements. Both of the elements 73 may be integral with the rod 72, or one of both of said elements 73 may be a separate piece, say threaded secured to said rod. Each of the rings 74 also passes through an aperture in the handle near an end thereof; such handle, designated 75, being indicated as an over-the-shoulder strap.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new, and desire to secure by United States Letters Patent is:

1. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line.
2. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line.
3. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, said handle being an over-the-shoulder strap.
4. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body having a widely openable mouth, one such mouth along the top of the body and the other such mouth along the bottom of the body, and there being a slide fastener closure for each of said mouths.
5. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly.
6. A handbag comprising a bag body having between its opposite side walls a partition structure to divide the main interior of the said body into two main interior subdivisions either of which may be located above the other according as the said body is rotated through 180° about a line substantially parallel to the direction of ex-

tension of said partition structure, and carrying means for the said body including a handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly, there being provided four independently operable slide fasteners each for closing one of said four mouths.

6. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly, there being provided four independently operable slide fasteners each for closing one of said four mouths, each compartment having therein a plurality of pockets all having their mouths facing in the same direction as is faced by the mouth of that compartment.

7. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly, there being provided four independently operable slide fasteners each for closing one of said four mouths, each compartment having therein a plurality of pockets all having their mouths facing in the same direction as is faced by the mouth of that compartment, certain of said pockets having closable mouths.

8. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a

5 about a line substantially parallel to the direction of extension of said partition structure, and carrying means for the said body including a handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly, there being provided four independently operable slide fasteners each for closing one of said four mouths, each compartment having therein a plurality of pockets all having their mouths facing in the same direction as is faced by the mouth of that compartment, certain of said pockets having closable mouths, there being a separate slide fastener for each of the last-named mouths.

9. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body having a widely openable mouth, one such mouth along the top of the body and the other such mouth along the bottom of the body, and there being a slide fastener closure for each of said mouths, each compartment having therein a plurality of pockets all having their mouths facing in the same direction as is faced by the mouth of that compartment.

10. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a handle and means for pivotally connecting the end portions of said handle to the ends of the bag at points substantially contained in said line, each of said two main interior subdivisions of the said body having a widely openable mouth, one such mouth along the top of the body and the other such mouth along the bottom of the body, and there being a slide fastener closure for each of said mouths, each compartment having therein a plurality of pockets all having their mouths facing in the same direction as is faced by the mouth of that compartment, there being a slide fastener for a pocket in at least one of said compartments.

11. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a

handle and means for pivotally connecting the end portions of said handle to the ends of the bag at points substantially contained in said line, each of said two main interior subdivisions of the said body having a widely openable mouth, one such mouth along the top of the body and the other such mouth along the bottom of the body, and there being a slide fastener closure for each of said mouths, each compartment having therein a plurality of pockets all having their mouths facing in the same direction as is faced by the mouth of that compartment, there being a slide fastener for at least one pocket in each of said compartments.

12. A handbag comprising a bag body having between its opposite side walls a partition structure to divide the main interior of the said body into two main interior subdivisions either of which may be located above the other according as the said body is rotated through 180° about a line substantially parallel to the direction of extension of said partition structure, and carrying means for the said body including a

handle and means for pivotally connecting the end portions of said handle to the ends of the bag at points substantially contained in said line, each of said two main interior subdivisions of the said body being subdivided into two compartments by a wall structure intermediate said side walls of the bottom, the last-named wall structure intersecting said partition structure, thereby to provide four of said compartments two of which have mouths facing downwardly when the other two thereof have mouths facing upwardly, there being provided four independently operable slide fasteners each for closing one of said four mouths, each compartment having therein a plurality of pockets all having their mouths facing in the same direction as is faced by the mouth of that compartment, the pockets in each compartment including one pocket with a closable mouth, and there being a slide fastener for each of the last-named pockets.

FRANCES VICTORIA LEWIS.
